UNITED STATES PATENT OFFICE.

FREDERICK J. ESTES, OF OAKLAND, CALIFORNIA.

DESIGN FOR A LAMP.

Application filed March 20, 1929. Serial No. 30,529. Term of patent 14 years.

To all whom it may concern:

Be it known that I, FREDERICK J. ESTES, a citizen of the United States, residing at Oakland, in the county of Alameda and State of California, have invented a new, original, and ornamental Design for Lamps, of which the following is a specification, reference being had to the accompanying drawing, forming part thereof.

Fig. 1 is an end elevation of a lamp, showing my new design.

Fig. 2 is a side elevation of a lamp, showing my new design.

I claim:

The ornamental design for a lamp as shown.

FREDERICK J. ESTES.
